MICROMETER LAPPING GUIDE

Earl D. Wilcox, Marlboro, and Robert E. Hunt,
Northboro, Mass.

Application February 20, 1946, Serial No. 648,867

1 Claim. (Cl. 51—241)

1

This invention relates to lapping micrometers and more particularly to a guide for the lapping tool.

The primary object of the invention is to insure the correct lapping of the anvil and the spindle of a micrometer and accurately dispose the faces of the anvil and spindle perpendicular to the longitudinal axis of the spindle.

Through use of the adjacent ends of a micrometer anvil and its cooperating spindle become worn and it is not infrequent that these adjacent surfaces get out of line so that they do not lie perpendicular to the axis of the spindle. When so worn the micrometer loses its accuracy, and fails as a precision tool with the result that it must be subjected to a lapping process to bring the faces of the anvil and the spindle back to parallelism and perpendicular to the axis of the spindle.

Another object of the present invention is to enable the ordinary mechanic skilled in the use of micrometers to lap the adjacent surfaces of the anvil and the spindle, and to bring them back to parallelism and accurately perpendicular to the axis of the spindle.

The above and other objects may be attained by employing this invention which embodies among its features a sleeve adapted to encircle the spindle of a micrometer, the ends of the sleeve being perpendicular to the axis of the spindle of the micrometer and means to fix the guide to the spindle so that a lapping tool may be introduced between the end of the guide and the anvil of the micrometer and operated in a plane perpendicular to the axis of the spindle so as to insure accuracy of the anvil.

Other features include having established the perpendicular relationship of the face of the anvil with the axis of the spindle, reversing the lapping tool, removing the sleeve and proceeding to lap the end of the spindle using the finished face of the anvil as the guide for the lapping tool.

In the drawings:

Figure 1 is a side view of a micrometer showing this improved lapping tool in place on the spindle thereof, the parts of the tool being shown in section to more clearly illustrate the details of construction.

Figure 2 is a perspective view of the lapping tool employed in conjunction with my sleeve and tool guide.

Figure 3 is a perspective view of a modified form of a lapping tool employed when the span of the micrometer demands a lapping tool of greater thickness.

2

Figure 4 is an enlarged transverse sectional view taken substantially along the line 4—4 of Figure 1, and

Figure 5 is a fragmentary perspective view 5 through the sleeve.

Referring to the drawings in detail a micrometer designated generally 10 comprises a substantially C-shaped frame 11 carrying at one end an anvil 12 and its opposite end a socket 13 in which the micrometer spindle 14 is mounted. As in conventional micrometers the spindle 14 aligns axially with the anvil 12 and is advanced or retracted with relation to the anvil through the medium of the thimble 15. The equipment so far discussed is of conventional form as will be readily recognized.

In order to lap the ends of the anvil 12 and the spindle 14 of the micrometer I employ a lapping tool designated generally 16 which comprises a disk shaped body 17 carrying an axial boss 18 of somewhat lesser diameter than the body 17 and formed on the end of the boss 18 is the lapping surface 19 which is adapted to engage the surface to be lapped. It will be understood that the lapping face 19 and the opposite face of the disk 17 lie in spaced parallel planes.

In order to guide the lapping tool 16 and hold the face 19 in proper lapping engagement with the end of the anvil 12 I employ a sleeve 20 having a bore 21 of somewhat greater diameter than the diameter of the spindle 14. Formed at opposite ends of the sleeve 20 are upset portions 22 which extend into the bore to provide guide faces 24 and 25 which lie perpendicular to one another, to form and effect a V-block which partially embraces the spindle 14 when the device is in use. Extending radially through the sleeve 20 diametrically opposite the apex of the V formed by the faces 24 and 25 is a set screw 26 having a knurled head 27 by means of which the screw may be turned so that its inner end effects clamping engagement on the spindle 14. Opposite end faces 28 of the sleeve 20 are machined or ground to perfect parallelism, and to lie perpendicular to the axis of the sleeve, and hence the axis of the spindle 14 as established by the surfaces 24 and 25.

When micrometers of greater size are to be lapped I employ instead of disk 17 a cylindrical body 29 carrying at one end a boss 30 having a lapping face 31 which lies parallel to the opposite end of the body 29.

In use the sleeve 20 is mounted on the spindle 24 as illustrated in Figure 1 after which the lapping tool 16 is placed in the position shown in Figure 1 with the back wall of the disk resting on

the end surface 28 of the sleeve 20 and the lapping surface 19 in contact with the anvil 12. Upon operating the lapping tool 16 in the ordinary manner the face of the anvil 12 facing the end of the spindle 14 will be brought into a plane lying perpendicular to the axis of the spindle. Having thus established and trued the face of the anvil 12, the sleeve 20 is removed from the spindle 14 by loosening the set screw 26 and extracting the spindle from the sleeve after which the lapping tool 16 is reversed so as to rest against the trued surface of the anvil 12 with the lapping face 19 contacting the end of the spindle 14. In this position the lapping of the spindle may proceed and its absolute parallelism with the adjacent face of the anvil 12 will be assured. In as much as the face of the anvil 12 has already been established as perpendicular to the axis of the spindle it is obvious that when the two faces are parallel the spindle face must also be perpendicular to its axis.

While in the foregoing there has been shown and described the preferred embodiment of this invention it is to be understood that minor changes in the details of construction, combina-

tion and arrangement of parts may be resorted to without departing from the spirit and scope of the invention as claimed.

We claim:

5 A micrometer lap guide comprising a sleeve adapted to encircle the spindle of a micrometer, said sleeve having a bore of greater diameter than the diameter of the spindle which it encircles, bearings at opposite ends of the sleeve for engaging the micrometer spindle, a clamp screw entering the sleeve for cooperation with the bearings to hold the sleeve on the spindle and at least one end surface of the sleeve lying in a plane perpendicular to the axis of the spindle and the sleeve.
